UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

IMPACT-ILLUMINATING BULLET.

1,088,025.

Specification of Letters Patent. Patented Feb. 24, 1914.

Application filed October 3, 1913. Serial No. 793,124.

To all whom it may concern:

Be it known that I, THOMAS C. JOHNSON, a citizen of the United States, residing at New Haven, in the county of New Haven 5 and State of Connecticut, have invented a new and useful Improvement in Impact-Illuminating Bullets; and I do hereby declare the following, when taken in connection with the accompanying drawings and 10 the characters of reference marked thereon, to be a full, clear, and exact description of the same, and which said drawings constitute part of this application, and represent, in—

15 Figure 1, a view partly in side elevation and partly in central longitudinal section of one form which an impact-illuminating bullet constructed in accordance with my invention may assume. Fig. 2, a view in transverse section on the line *a*—*b* of Fig. 1. Fig. 20 3, a view partly in side elevation and partly in longitudinal section of a modified form which my improved bullet may assume. Fig. 4, a corresponding view showing my invention embodied in a jacketed bullet.

25 My invention relates to an improvement in that class of bullets charged with a composition flashing upon the impact of the bullet and thus illuminating the place where it struck for the information of the user of 30 the gun from which it was fired, the object being to produce a superior bullet constructed with particular reference to reliability of operation in the magazine and mechanism 35 of the gun, and to the production at the time of impact, with an exceedingly brilliant illumination, of a circular area the center of which is the point of impact.

With these ends in view, my invention 40 consists in an impact-illuminating bullet having certain details of construction which will be hereinafter described and pointed out in the claims.

In carrying out my invention as shown in 45 Figs. 1 and 2, I form a relatively large concentric pear-shaped composition-cavity 2 formed well forward in the nose 3 of the bullet 4 and having its outer end entirely closed so as to give the bullet the same unbroken exterior contour at the point as ordinary bullets have, whereby my improved 50 bullet is prevented from being fouled in the

magazine or mechanism of the gun in which it is used. This cavity is partially filled with a charge 5 of any suitable flash-light composition, the character of which may be varied according to well-understood principles to meet predetermined requirements. Preferably, as I am now advised, I shall employ a flash-light composition giving a 60 brilliant, intense illumination at the moment of impact with or without a report and with the production of the minimum amount of smoke which will follow the illumination and not obscure it. The composition-cavity 65 2 is made large enough to provide for an ample charge 5 of flash-light composition as well as an air-space 6 which is located directly between the charge and the apex of the bullet. This air-space may of course be 70 varied in size by varying the size of the cavity 2 and the mass of the charge 5.

In the modified form shown by Fig. 3 of the drawings, the bullet 7 is formed with a concentric cavity having a cylindrical rear 75 end 8 and a conical forward end 9 produced by entirely closing the outer end of the cavity after the introduction of the flash-light composition 10 into its rear end, the cavity being cylindrical throughout its 80 length as initially formed. The conical forward end 9 of the cavity forms an air-space 11, which is located directly between the flash-light composition 10 and the apex of the bullet.

In Fig. 4 I have shown my invention applied to a jacketed bullet, the soft-metal core 12 of which is formed at its forward end with a concentric cylindrical cavity 13 receiving a plug-like mass 14 of flash-light 90 composition. In this construction the air-space 15 between the composition 14 and the closed apex 16 of the bullet is produced by the hollow point of the jacket 17, whereby the cavity 13 is left of full diameter at its 95 outer end.

I claim:

1. As a new article of manufacture, an impact-illuminating bullet containing in its nose a cavity receiving a charge of flash-light composition, and provided with an air-space located directly between the composition and the apex of the bullet.

2. As a new article of manufacture, an

22
impact-illuminating bullet having a concentric cavity receiving a charge of flash-light composition, and forming an air-space which separates the composition from the closed apex of the bullet.

3. As a new article of manufacture, an impact-illuminating bullet having a closed concentric composition-cavity formed in its nose and receiving a charge of flash-light

composition separated from the closed apex 10 of the bullet by an air-space.

In testimony whereof, I have signed this specification in the presence of two subscribing witnesses.

THOMAS C. JOHNSON.
